COLLAPSIBLE EASEL

Sanford L. Goldman, Long Beach, N. Y.

Application August 19, 1948, Serial No. 45,081

1 Claim. (Cl. 40—152.1)

1

My present invention relates generally to portable display racks, stands or easels, and more particularly to a collapsible display easel or rack or picture frame.

It is an important object of my present invention to provide a portable collapsible picture display easel, rack or frame which is provided with a slidable transparent cover so constructed and arranged that it effectively retains a display sheet in position without any necessity for the cover to be locked to the easel at any point thereof by special devices.

Another important object of my present invention is to provide a display stand or rack which is designed to be folded up and put away when not in use, but when in use it opens up and is supported by a web hinge located in a base of a triangle, and a transparent plastic frame or cover provided with a long, narrow hook at its upper edge cooperating with an extension of one side of the triangle to retain a display sheet under the cover.

Another object of my invention is to provide a collapsible display easel which essentially comprises a support board and a hinged rear board, there being provided a transparent cover of the same dimensions as the support board, the cover having a long, narrow hook section adjacent its upper edge so that it can hang freely from the support board top edge, the cover retaining snugly between it and the support board any desired sheet to be displayed.

Still other objects and features of my invention will appear as the description proceeds, it being understood that while the following description and drawing illustrate a preferred embodiment they do not limit the scope of the invention as defined in the appended claim.

In the drawing:

Fig. 1 is a perspective view of my collapsible easel;

Fig. 2 is a side view of the easel, the lower half being broken away; and

Fig. 3 is a rear view of the easel, portions being broken away.

Referring now to the accompanying drawing, wherein like reference numerals in the several figures denotes similar elements, my novel portable display rack or picture frame comprises a support board or plate 1 of generally rectangular configuration. The board 1 is preferably composed of heavy cardboard provided with a relatively heavy canvas facing on both sides. Of course, if desired, the board 1 may be made of aluminum sheeting, light wood, thin plastic

2

sheeting or any other available light material. The board 1 is provided with a support which preferably consists of an upper rectangular board 2 hinged, as at 3, to a lower substantially square board 4. The total area of the boards 2 and 4 equals that of board 1.

The boards 2 and 4 are each separate heavy cardboard pieces, preferably similar to the thickness of board 1. A canvas facing envelops the boards 2 and 4. The hinge line 3 is provided at the adjacent horizontal edges of boards 2 and 4. Of course, the horizontal hinge 3 between the sections or boards 2 and 4 may be provided in any other suitable and known manner, as by conventional hinges. Further, where desired, the upper section 2 may be omitted, and the lower section or leg 4 may be directly hinged to the front board 1 at about the horizontal line 3.

The section 2 is secured to the rear face of board 1 by any suitable cement or plastic composition. Any other suitable securing device may be utilized for these sections 2 and 1. The hinged board 4 is restrained against backward motion beyond a certain point by the foldable web 5, as shown in Fig. 1. The web 5 preferably consists of extensions of the canvas facings of boards 1 and 4. The web 5 has a fold line 6 running across it at the middle thereof. This permits the web 5 to act as the base of triangle 4, 1, 5 when the web is fully spread as shown in Fig. 1. However, when the rear section 4 is pushed against the board 1 the web 5 folds upward into two halves. This is due to the fold line 6 and the hinge lines 7 and 8. The foldable canvas web 5, therefore, permits the display rack to be folded up and put away when not in use, but when in use it opens up (as shown in Fig. 1) and is supported by rear section 4 and base web 5.

The transparent rigid cover 9 is made of any suitable plastic material, for example the product sold under the brand name "Lucite," and has an area equal to that of the front board 1. The cover 9 is provided with a rear hook extension 10 which is closely spaced from the cover. The top edge 11 of the cover 9 is curved thereby providing a finished curved top edge for the display rack. The space between hook extension 10 and cover 9 is just sufficient to house the portions of the rack located above horizontal hinge 3 (Fig. 2). This elongated, narrow hook of cover 9 fits snugly over the rack, and thus functions to keep the cover 9 closely against the front face of board 1. The relation of the rear sections is shown in Fig. 3, the display sheet 11 being shown positioned on front board 1. In Fig. 3 the display

sheet 11, which may carry any material desired and for example the picture 12, is shown projecting down between front board 1 and transparent cover 9.

The cover 9 and its upper hook 10 is preferably made as a single unit. The thickness of cover 9 is about equal to the thickness of front board 1. While rigid, the cover 9 and its hook 10 possess a degree of flexibility. It is found in actual usage that the display sheet 11 is retained in a chosen position on board 1. The entire display rack has a neat appearance, and is very simply fabricated. When folded, that is with web base 5 folded between board 1 and rear leg 4, the rack may be used as a picture frame which can be mounted on a wall. To remove the cover 9, it is only necessary to slide the cover upwards (Fig. 2) to release the hook 10 from the sections 2 and 1.

What I claim is:

In a picture display stand or frame, a solid front board, a pair of upper and lower rear boards hinged together across the front board, the board above the hinge being secured to the rear face of the front board adjacent the top

edge thereof, a foldable web secured to the lower edges of the front board and lower rear board, a transparent rigid plastic cover plate provided with an elongated narrow rear hook at its top edge, said cover plate having its remaining edges all free, said hook being removably engaged over the said secured front board and rear upper board, said cover plate securely retaining a display sheet between it and the front face of the front board.
